DECODING SYSTEM

Matthew H. Loughridge, Bogota, N. J.; William R. Lockridge, administrator of Matthew H. Loughridge, deceased

Application November 5, 1941, Serial No. 417,969

19 Claims. (Cl. 177—353)

This invention relates to direct decoding systems and its purpose is to translate a code into readable characters corresponding to the characters from which the code was produced. Coding systems are used commercially in a variety of forms and one form extensively in use uses a scanner system of decoding; that is, a scanner is made according to the code to be obtained and then all the codes of a group are compared with this scanner until a matching code is found, which is the answer to the scanner. The present invention takes any code by itself and translates this code directly into the subject from which the code originated. As coding systems are usually applied to a large number of documents or similar articles, each of which is indexed by a different code, it is apparent that in direct decoding the system must be capable of producing individual answers corresponding with the capacity of the code. An object of the present invention is to secure these answers in a coded system in a simple arrangement of apparatus which may be operated electrically, or mechanically, or by a combination of both. A further object of the invention is to provide for decoding systems that differ from each other in the arrangement of the code.

Other objects of the invention and the operation of the systems will be more particularly understood from the following specification and the accompanying drawings, in which:

Figs. 1, 2 and 3 are graphic representations of one form of code which, numerically, codes units, tens and hundreds;

Fig. 4 is a diagram of the electric apparatus and circuits used to decode Figs. 1, 2 and 3 and produce the answer by rotary translating devices;

Fig. 5 is another form of code;

Fig. 6 is a circuit diagram of the electric apparatus with the translating devices used to decode the code in Fig. 5;

Fig. 7 is another form of code, and

Fig. 8 is an arrangement of electric circuits for operating decoding devices for the code in Fig. 7;

Fig. 9 is another form of code;

Fig. 10 is a code supplementary to Fig. 9, and

Fig. 11 is a diagram of the electric circuits used for decoding the codes in Figs. 9 and 10.

In the drawings, the code system is developed graphically for each circuit so that the operation can be readily followed from the arrangement of squares. The code system has a base indicated at the end by the numerals zero to nine inclusive and the reading of the code is obtained

from the longitudinal lines on the base projected from each numeral. Cross lines are provided with a circle thereon to indicate the position in the base of the code in which a code impulse is produced. These positions are indicated by the numerals along the edge of the graph representing the code, making an easy method of designating the code.

The following variations in the application of 10 the code systems are shown:

(a) A separate code for each code translating device, one character only being used at a time;

(b) A separate code for each translating device operating progressively to register in units, 15 tens, hundreds, etc.;

(c) A code having a single base with three characters located on the base to establish the code and operating a plurality of translating devices;

20 (d) A code having a main base with a plurality of characters located thereon, one being in ascending order relative to the other and a supplementary base having a code character thereon in descending order, relative to one of the characters on the main base operating translating means for decoding.

For the purpose of applying this invention, any 30 of the commercial arrangements of coding may be used, one form of which is shown in application Serial No. 248,894, filed December 31, 1938, now Patent 2,269,293, Jan. 6, 1942. In the arrangement shown it is only necessary that the code to be decoded establishes operating circuits for a bank of relays which operates the decoding apparatus. In the drawings, one side only of the operating circuit is shown as this is sufficient to show the method of control.

35 A device known as a "motorstat," as shown in application Serial No. 282,833, filed July 4, 1939, or shown in Serial No. 315,300, filed January 24, 1940, is used as the translating device operated by the controlling relays to give the decoding answer. This apparatus is used because it operates through an air gap without a mechanical mechanism which simplifies the operation and reduces the cost. There may be, of course, conditions arise where some of the commercial form of tabulating machines would be required instead of this translating device.

40 45 50 An important consideration in applying this invention is the base of the code system. In the drawings this base is limited to 10 and the movable characters thereon forming the code is limited to 3. The capacity of a code of this type and the method of expanding it is described in

application Serial No. 205,186 filed April 30, 1938, now Patent 2,266,779, Dec. 23, 1941. The present code system and the circuits associated therewith can be expanded in a similar manner and are fully contemplated in the present invention.

The base of the code is numbered from zero to nine and this numbering is maintained throughout for the chain of apparatus that originates with the code character and ends with the translating device. This apparatus repeats for each position of the base so that a description of the operation of one circuit is sufficient for the repeating circuits that follow. A code is established when each character of the code system on the transverse line energizes its controlling circuit and several characters may operate in this way at the same time.

A bank of relays is provided for the code, one relay corresponding to each position of the code. Each relay when energized energizes a corresponding coil of the motorstat to stop it in a position that will correspond with this relay and in turn correspond with the location of the code character on the base.

When the code is to be translated into a series of numbers following each other a separate translating device may be used for each number operated by a single bank of relays, said translating device being selectively brought into operation in cooperation with the code character to be registered.

A code system with a single base and with a single bank of decoding relays may be used to locate a plurality of code characters provided they are arranged in ascending order or descending order so that they do not become misplaced on the base of the code. By the use of a supplementary base this arrangement may be applied for decoding in both ascending and descending orders.

Decoding a code using one character on the base

The system shown in Figs. 1 to 4 is an arrangement for decoding a code in units, tens and hundreds in which only one character is used in the code base at a time. The system comprises a bank of ten decoding relays for the units indicated by 11, a second bank of ten decoding relays for the tens, indicated by 12, and a third bank of ten decoding relays for the hundreds, indicated by 13. A row of contact fingers 14 are provided, one for each position of the base running from 0 to 9 and each finger is connected by a conductor 15 to the corresponding relay of the bank for the particular code.

The base of the code is indicated by the figures opposite 16 and the reading of any particular code on the transverse lines is indicated by the figures on the side row opposite 17. Each figure corresponds with the base character which effectively engages the corresponding contact finger 14 and is indicated by 18. It will be convenient in considering the operation of the system to assume that where the circle 18 appears a contact is established with a source of energy to energize the corresponding finger 14 and the relay associated therewith; the return circuit is not shown in the drawings. All contact fingers that do not register with a code character as indicated at 18 remain insulated and the relays associated with these contact fingers remain deenergized.

A source of alternating current is obtained from the transformer 21 which, on one side, ener-

gizes conductor 22 and conductor 25. Conductor 25 connects through a back contact 28 to the contact finger of each of the bank of relays, 11, 12 and 13, the relay contacts being connected in multiple circuit, in the deenergized position to the source of alternating current. A full wave rectifier 23 is connected across the mains 22, 26 of transformer 21 and through conductor 24 and connection 29 establishes a circuit through each 10 of the contacts 27 of the bank of relays 11, 12 and 13 in the energized position so that energizing any of these relays changes the circuit controlled by the relay contact 27 from the source of alternating current to the unidirectional current from rectifier 23.

A circuit on conductor 30 is provided from the pivot end of the contact finger 27 of each relay to a terminal board 33 for the hundreds and provided with terminals numbered corresponding to the relays of the bank. A similar terminal board 20 is provided at 32 for the relays in the bank 12 and another similar terminal board is provided at 31 for the relays in bank 11.

A rotary responsive device known as a motorstat 25 is provided at 34 and connected with the terminal board 31 to indicate units, a second motorstat is provided at 35 and connected with the terminal board 32 to indicate tens and a third motorstat is provided at 36 connected with terminal board 33 to indicate hundreds. Each motorstat comprises a non-magnetic rotor 37, usually made of aluminum, and having a magnetic insert at 43 which as the rotor rotates registers with each pole of the stator indicated by the numerals 0 to 9. The stator may be energized with alternating current to drive the rotor 37 and provided with any phase splitting arrangement that is commonly used in motors of this kind. In the drawings a shading coil 40 is provided for this purpose. The poles 39 of the stator have a common return circuit on conductor 41, connecting to 26 and on conductor 26', also connecting to 26. Each coil of the stator is connected by conductor 42 with the corresponding terminal 35 of the terminal board. When all the relays of the bank which controls one of these devices are deenergized all the coils are energized with alternating current and the rotor is driven thereby. When one of these relays is energized the coil which it controls is disconnected from the source of alternating current and connected with the source of direct current. The pole of the stator energized by this coil is energized with one polarity and attracts the magnetic device 43 when it comes into register with this pole, thereby stopping the rotation of the rotor at a point selected by the particular pole which is energized and which in turn is determined by the position of the code character on the base. The return conductor 26 connects to transformer 21 and also to rectifier 23 thus forming the return circuit for both the alternating and direct current. The operation of this system will readily be understood by considering the code on the first line in Fig. 1 which reads 7 and energizes relay 7 of bank 13 which energizes pole 7 of the stator 36 with direct current and positions this device to read 7. The second code, Fig. 2, reads 5 and energizes relay 5 of bank 12 which energizes coil 5 of stator 35 with direct current and positions this device to read 5; also Fig. 3 reads code 5 on the first line and energizes coil 5 of device 34 to produce a corresponding reading by this device. The code thus set up is represented by 755 and this reading is 75 produced by the translating devices 34, 35 and

36. The code in the second line in Figs. 1, 2 and 3 reads 416 and the devices 34, 35 and 36 set up this answer when these codes are brought into operation. If these codes are placed on a card it is apparent that each card can be decoded by itself into the figures from which the code was derived. In this arrangement it will be noted that the translating devices 34, 35 and 36 are independently operated and may operate at the same time and the code is not restricted to an ascending or descending order of numbers.

Decoding a plurality of codes progressively

In Figs. 5 and 6 the translating devices producing the final answer are not operated at the same time but instead are operated progressively to read units, tens and hundreds and are operated by a single bank of decoding relays controlled by a selective arrangement.

The code Fig. 5 is provided with selective contacts indicated by U, T and H, one for each code and a corresponding set of contact fingers U, T and H are provided to be energized by the contacts of the code. A contact finger U connects by conductor 44 with the selective relay 45; contact finger T connects by conductor 46 with selective relay 47 and contact finger H connects by conductor 48 with selective relay 49. The selective relays control the translating devices 34, 35 and 36 on their return circuit by conductor 26H for device 36 which through contact finger 52 of relay 49 in the energized position connects to the common conductor 26. Conductor 26T for device 35 connects through contactor 51 in the energized position to the common conductor 26 and conductor 26U connects the return circuit of device 34 through contact finger 50 in the energized position to conductor 26.

The translating devices 34, 35 and 36 are connected in multiple circuit with the contact fingers 27 of the bank of decoding relays 13, through conductor 30, branch 30a to 34, branch 30b to 35 and branch 30c to 36. Each relay energized changes the circuit for a coil of the devices 34, 35 and 36 from the alternating current source on wire 25 to wire 24 and the battery 23a.

In operation it will be noted that the code set up on the first transverse line in Fig. 5 is indicated by 1 and energizes relay 1 and at the same time contact finger H is energized and relay 49, which closes the return circuit of device 36, while the return circuit of devices 34 and 35 remains open. In this position device 36 is set to indicate code 1 and then the code is advanced to the second line which brings the character 3 into circuit and energizes relay 3 and, at the same time, contact finger T is energized with relay 47 which closes the return circuit of device 35 while the return circuit of 34 and 36 remains open. This causes the device 35 to register the code 3. When the code is advanced to the third line the character 5 operates to energize relay 5 and the contact finger U is energized with relay 45 which sets up the return circuit for device 34 while the return circuit of 35 and 36 remains open. In this way the code 735 is registered progressively through the same bank of decoding relays. In the same way any code may be registered by the translating devices and the code is not restricted to an ascending or descending order of numbers. The relays 45, 47 and 49 also control the alternating current from the transformer 21 on the return circuit 26, so that the devices 34, 35 and 36 are first positioned by the alternating current and

then stopped by the direct current in the selected position.

Decoding a code with a plurality of characters

5 A code that uses one character only positioned on the base is limited to the number of positions on the base but a code that uses several characters at a time on the same base has a much enlarged capacity. A code of this type is shown in Fig. 7 and its application in Fig. 8. This code has a base with ten positions running from 0 to 9 and two additional positions indicated by a and b. Three characters are located on the base in the various positions to establish the code and each code must have at least one character in a different position from all the other codes.

This code starts at 0 and goes to 9, it omits 10 and runs from 11 to 19 where it omits 20 and 21 and then runs from 22 to 29, etc., the omitted numbers being indicated at x, y and z. The reason for these omissions arise from the fact that the numbers have to be applied in ascending order as the same base is used for units, tens and hundreds. The tens and hundreds are indicated by a and b and the units by the numerals from 0 to 9 and each time that 9 is reached by the units the tens or the hundreds are advanced one and as this advance is maintained the corresponding positions for the units is taken up so that these figures of the lower order have to be omitted. This code, as indicated at the right hand end of Fig. 7, runs to 789.

A bank of relays 11 is provided to correspond with the positions on the base of the code and relays a and b are added, connecting with the contact fingers a and b. The bank of relays 11 control a repeating circuit by the contact fingers 55, 56 and 57 of each relay, which, through conductor 58 repeats from relay to relay on the first row of fingers, through conductor 59, repeats from relay to relay on the second row of fingers and through conductor 60 repeats from relay to relay on the third row of fingers. When any relay is energized the conductor 61 at that relay transfers the circuit from the first row of fingers to the second row of fingers, also conductor 62 transfers the circuit in the second row of fingers to the third row of fingers. The first row of fingers 55 at each relay connects by conductor 63 with the terminal board 33 the second row of fingers 56 at each relay connects by conductor 64 with the terminal board 32 and the third row of conductors 57 connect by conductor 65 with the terminal board 31. The terminal boards are operatively connected to the translating devices as indicated in Fig. 4.

The position of the relays with reference to the position of the code characters on the base of the code starts from the left and the operation of the translating devices operated by the relays is determined by the order in which the relays are energized from the left. The first relay in the bank that is energized from the left energizes a circuit connected with terminal board 33 through its first contact 55. The circuits on conductor 64 and 65 at this relay are not established. The second relay in the bank that is energized establishes the circuit on conductor 64 to terminal board 32, while the circuits on conductors 63 and 65 of this relay are open and the third relay in the bank that is energized establishes the circuit through conductor 65 to terminal 31 while conductors 63 and 64 at this relay are open. No circuit can be established by energizing more than

three relays when three characters are used in the code.

If a code reading in units is to be established the tens and hundreds should indicate 0; for this reason the first contact of relays *a* and *b* connect to the 0 coil. Relay 0 when energized connects to the 0 coil on terminal 31 but this circuit can be established only when relays *a* and *b* are energized.

The units code is indicated by the base 16 while the tens code is indicated by 16*a* and as 0 in this code begins opposite *b* this code is displaced by one number with reference to code 16 so that tens are read from the figures in 16*a* and the units from figures in 16.

The operation will be understood by considering code 7. In this code contact fingers *a* and *b* are energized and contact finger 7 in the units code which energizes relays *a*, *b* and 7. *a* and *b* restore the translating device connected to the tens and hundreds to 0 while 7 energizes coil 7 of the units translating device and registers this number. If the code is 458, relay 8 is energized to register the units, relay 4 which is opposite contact 5 in the tens is energized and relay 2 which is opposite coil 4 in the hundreds is energized. These relays operate the translating devices 34, 35 and 36 to register the numbers which correspond with the code and are obtained from the base of the code.

This provides a relatively simple method of decoding a system that runs into a large number of codes but is limited to numbers arranged either in ascending or descending order. A code translated by the devices 34, 35 and 36 may be scrambled into a code of another type, for instance using letters instead of figures to designate the code and which may be retransmitted in this form.

Decoding with code numbers in ascending and descending order

The code system in Figs. 9, 10 and 11 operates similarly to Figs. 7 and 8 but by the use of an auxiliary base the code between the tens and the units operates in both ascending and descending orders. In Fig. 9 the units code is read by the numbers opposite 16 and also by the corresponding numbers in Fig. 10 at the base of the code; the tens are read by the numbers opposite 16*a* and the hundreds are read by the numbers opposite 16*b*. Since the code starts opposite the base lines *a*, *b* and 0 representing 0 in the code and in Fig. 9 the code characters move progressively across the base, the units first, followed by the tens and then by the hundreds, it will be seen that the reading for the position of the tens and hundreds is displaced successively by one position in the code so that, for instance, a units code in position 3 in the units corresponds to position 4 in the tens and to position 5 in the hundreds. The indicators of the code base at 16, 16*a* and 16*b* are for convenience in explaining the operation.

A bank of decoding relays 11 are each connected by the conductors 15 with the contact fingers 14 to operate each relay by its corresponding character in the code. Also a second bank of relays 11*b* are provided and operated by the contact fingers 14' according to the position of the characters in the base of the supplementary code, Fig. 10.

When the code numbers occur in ascending order from the units to the tens and the tens to the hundreds the code is registered by the relays 11, the operation corresponding to Fig. 8. The

missing code between 18 and 22 appears at 20 and 24 in the supplementary code, Fig. 10, also the missing code 20, 31 and 32 between 28 and 33 appears in Fig. 10. The part of the code that appears in Fig. 10 applies to the units only and this part operates in conjunction with the tens and hundreds in Fig. 9.

In the operation for the code appearing in Figs. 9 and 10, two of the relays in bank 11 are energized by the tens and hundreds characters in code 9 and one relay in 11*b* is energized by the code character in Fig. 10. The bank contact of relay 9 in bank 11 at 57 connects with conductor 70 which energizes contact finger 71 of the first relay in bank 11*b* and by conductor 73 is repeated from relay to relay in this bank until an energized relay is reached at which point the conductor 72 connects to terminal board 31 and energizes the corresponding coil of the translating device to indicate units. The code characters in the supplementary base 10 are of a lower order than the code characters for the units in Fig. 9. It will be noted that codes between the units and tens can be applied in both ascending and descending orders.

In general the decoding systems herein described can be applied to apparatus operated mechanically as well as by the electric system shown and a full range of equivalents is contemplated by the present invention.

Having thus described my invention, I claim:

1. A de-coding system comprising a base having a plurality of positions for the characters of the code, means for establishing a code by the location of the code character on said base, a bank of relays, one for each position of the code, means for establishing the circuit of each relay by the code character having the location on the base corresponding to the relay, a rotary de-coding device controlled by said relays having driving means, and means controlling said rotary device by said relays to stop said device in a position corresponding with the relay that is energized.

2. A de-coding system comprising a base having a plurality of positions for the characters of the code, means for establishing a first code by the location of the first character on said base, means for establishing a second code by the location of the second character on said base, a first bank of relays, one for each position of the first code, a second bank of relays, one for each position of the second code, means for establishing the circuit of each relay in the first bank by the code character of the first code having the location on the base corresponding with the relay, means for establishing the circuit of each relay in the second bank by the code character of the second code having the location on the base corresponding with the relay, a rotary de-coding device controlled by each bank of said relays, and means for stopping said rotary devices in positions corresponding with the relays that are energized in each bank.

3. A de-coding system comprising a base having a plurality of positions for code characters in a row, means for establishing a first code by a character in the first row, means for establishing a second code by a character in the second row, a bank of relays, one for each position of the code, means for establishing the circuit of each relay by the code character having the location on the base corresponding to the relay, for one row at a time, a de-coding device having positions corresponding with the positions of said

base, means for operating said device to a position corresponding with the relay that is energized by the code character, and means for changing the operation of said relays from the first row of characters to the second row of characters.

4. A de-coding system comprising a base having a plurality of positions for code characters in a row, means for establishing a first code by a character in the first row, means for establishing a second code by a character in the second row, a bank of relays, one for each position of the code, means for establishing the circuit of each relay by the code character having the location on the base corresponding to the relay for one row at a time, a de-coding device for each row of characters each having positions corresponding with the positions of the base, means for operating the first device to a position corresponding with the relay that is energized by the code characters of the first row, and means for changing the operating of said relays to operate the second device in response to the relay that is energized in the second row.

5. A de-coding system comprising a base having ten positions for code characters, three code characters arranged on said positions to establish the code desired, a bank of ten relays, one for each of the positions of said base, means for selectively operating three of said relays by said code characters according to their location on the base, and a responsive device operated by any three of said relays energized and selectively de-coding all the codes set up by said characters.

6. A de-coding system comprising a base having ten positions for code characters, three code characters arranged on said positions to establish the code desired, a bank of ten relays, one for each of the positions of said base, means for selectively operating three of said relays by said code characters according to their location on the base, a responsive device for reading the code having three elements, means for operating the first element by the first relay of said bank from the entering end that is energized to a position corresponding with the relay in the bank, means for operating the second element by the second relay of the bank that is energized to a position corresponding to the position of the relay in the bank and means for operating the third element by the third relay energized to a position corresponding to the position of this relay in the bank.

7. A de-coding system comprising a base having ten positions for code characters, two code characters arranged on said positions to establish the code desired, a bank of ten relays, one for each of the positions of said base, means for selectively operating two of said relays by said code characters according to their location on the base, a responsive device for reading the code having a first element representing units and a second element representing tens and means operating the first element by the first relay of the bank that is energized and operating the second element by the second relay of the bank that is operated.

8. A de-coding system comprising a base having a plurality of positions, one code character located on said base representing units, a second code character located on said base representing tens and a third code character located on said base representing hundreds, said code characters being arranged in ascending order, a bank of re-

lays, one for each position of the base, means for selectively energizing a first relay of the bank in accordance with the position of the units character, means for selectively energizing a second relay of the bank in accordance with the position of the tens character and means for selectively energizing a third relay of the bank in accordance with the position of the hundreds character on the base, and a translating device operated by the first relay to indicate the units, by the second relay to indicate the tens and by the third relay to indicate the hundreds.

9. A de-coding system comprising a base having a plurality of positions, one code character located on said base representing units, a second code character located on said base representing tens and a third code character located on said base representing hundreds, said code characters being arranged in ascending order, a second base supplementary to the first base, supplementary code characters on the second base arranged in descending order, a bank of relays for each position of the first base, a supplementary bank of relays for each position of the supplementary base, means for selectively energizing a first relay of the bank in accordance with the position of the units character, means for selectively energizing a second relay of the bank in accordance with the position of the tens character and means for selectively energizing a third relay of the bank in accordance with the position of the hundreds character on the base, means for energizing a relay in the supplementary bank by the character in the supplementary base and means for registering the code in ascending order in the first base and for registering the code in descending order in the supplementary base.

10. A de-coding system comprising a main base having a plurality of positions, one code character located on said base representing units, a second code character located on said base representing tens, one of said characters being arranged in ascending order relative to the other on the base, a supplementary base having a plurality of positions, a code character located in said supplementary base in descending order from one of the characters in the main base, means controlled selectively by said characters, and translating means operated by said control means to indicate the code established by said characters when arranged both in ascending and descending order.

11. A de-coding system comprising a bank of relays normally deenergized and corresponding with the number of positions in the code, means for energizing each relay by a code character corresponding with its position in the code, and a translating device selectively operated by said relays and operated to a position to indicate hundreds by the first relay of the bank that is energized, operated to a second position to indicate tens by the second relay of the bank that is energized and operated to a position to indicate hundreds by the third relay of the bank that is energized.

12. A de-coding system comprising a bank of relays normally deenergized and corresponding with the number of positions in the code, means for energizing each relay by a code character corresponding with its position in the code and for energizing three of said relays at a time, a translating device selectively operated by said relays to indicate hundreds, tens and units, the first relay in said bank from the entering side operating said device to indicate hundreds, the next relay from the entering side operating said de-

vice to indicate tens and the third relay from the entering side operating said device to indicate units, the operation of the device by the following relays being dependent upon the operation of the preceding relays.

13. A de-coding system comprising a bank of relays normally deenergized and corresponding with the number of positions in the code, means for energizing each relay by a code character corresponding with its position in the code and for energizing three of said relays at a time, a second bank of relays normally deenergized, means for energizing each relay in the second bank by a code character corresponding to its position in the code, a translating device selectively operated by said relays to indicate the code, the relays in the first bank being interlocked so that the operation of the second relay is controlled by the first relay in the bank and the relays in the second bank controlling a circuit that is also controlled by the first bank.

14. In a decoding system, means for recording two codes in the order of units and tens, a bank of ten relays for each code selectively controlled by the codes, a translating device operated by the relays controlled by the units code and an independent translating device operated by the relays controlled by the tens code to decode the codes into the subject originally recorded by the codes.

15. In a decoding system, means for recording a code, a plurality of rotary means for decoding said code, means for continuously driving said rotary means, and means controlled by the code for stopping the rotary means at positions selected by the code for decoding purposes.

16. In a decoding system, means for recording three codes, a bank of relays for each code selectively controlled by the codes, and a translating device for each code controlled by the relays for the code, said translating devices operating independently for each code.

17. In a decoding system, means for recording a code having three changeable characters representing the subject coded, a bank of relays selectively controlled by said characters, three translating devices, one operated by the relays responsive to the first character, the second operated by the relays responsive to the second character, and the third operated by the relays responsive to the third character for reproducing the subject coded.

18. In a decoding system, means for recording a code having changeable characters that can be adjusted to represent any number of two figures, a bank of relays selectively controlled by said characters, and two translating devices independent of each other operated by said relays to positions corresponding with the code and having figures thereon for reproducing the numbers coded.

19. In a decoding system, means for recording a code on a first base, means for recording a code on a second base, a bank of relays selectively responsive to the code of the first base, a second bank of relays selectively responsive to the code of the second base, and a translating device operated independently by the relays controlled by the first base, or by the relays controlled by the second base.

MATTHEW H. LOUGHBRIDGE.
